UNITED STATES PATENT OFFICE.

WILLIAM OSCAR TEASDALE, OF MANILA, PHILIPPINE ISLANDS.

ELECTRIC-LIGHT PENDANT.

1,111,623.

Specification of Letters Patent. Patented Sept. 22, 1914.

Application filed January 19, 1914. Serial No. 813,005.

To all whom it may concern:

Be it known that I, WILLIAM OSCAR TEASDALE, a citizen of the United States, and a resident of Manila, Philippine Islands, have 5 made certain new and useful Improvements in Electric-Light Pendants, of which the following is a specification.

My invention relates to improvements in adjustable electric light fixtures, and it consists in the combinations, constructions, and arrangements herein described and claimed.

An object of my invention is to provide a holder for an electric lamp by means of which the lamp may be easily adjusted to 15 any position and may be firmly held in its adjusted position.

A further object of my invention is to provide a device of the character mentioned which is simple in operation and which may 20 be manipulated with very little effort.

Other objects and advantages will appear in the following specification and the novel features of the device will be particularly pointed out in the appended claims.

25 My invention is illustrated in the accompanying drawings forming part of this application in which—

Figure 1 is a side view of the device, Fig. 2 is a view of a modified form, Fig. 3 is a 30 view of another modified form, Fig. 4 is an enlarged sectional view, Fig. 5 is an enlarged face view of a portion of the apparatus, Fig. 6 is a section along the line 6—6 of Fig. 5, and Fig. 7 is a plan view, 35 showing the different positions of the lamp 30 on the line 7—7 of Fig. 1.

Referring now to Fig. 4, I have shown a casing 1 having a flange 2 arranged to be secured to the ceiling 3 where it may cover 40 the ordinary rosette (not shown). The casing is threaded internally at its bottom to receive the upper threaded end of a tube 4. The lower end of the tube 4 is threaded to enter the threaded socket 5 at the end of 45 a sleeve 6, which is shaped at its upper end, as shown at 6^x to be turned by a wrench. The lower end of this sleeve is provided with a series of tapered spring fingers 6^a arranged to engage the sides of a tube 7 which 50 is adapted to enter the tube 4, the tubes 7 and 4 forming telescopic members. A screw plug 8 which is provided with a head 8^a is carried by the upper end of the tube 7. The lower end of the sleeve 6 is threaded 55 to enter the threaded thimble 9 which is pro-

vided with an end having inner inclined walls 9^a arranged to engage the tapered spring fingers 6^a.

At the bottom of the tube 7 is secured an annular flange 10. A sleeve 11 is disposed about the tube 7. This sleeve is threaded to enter the threaded end of a thimble 12 having a portion 12^a arranged to engage the spring fingers 11^a which are integral with the sleeve 11. An oil inlet 13 is provided in the sleeve 11.

The sleeve 11 is threaded internally at its lower end to receive the threaded lug 14 of a laterally extending sleeve 15. The latter is arranged to slidably hold a tube 16 and is provided with a locking thimble 17 arranged to engage the spring fingers 16^a for locking the tube 16 in its adjusted position. The tube 16 is bent at 16^x and is connected by means of a hinged joint 18 with a tube 19 which is provided with an opening 20 for the admission of the flexible conductor 21. The tube 19 is threaded at 22 to fit a standard electric light socket.

From the foregoing description of the 80 various parts of the device the operation thereof may be readily understood.

The upper tube 4 is provided with a branch 4^x through which the flexible conducting cable 21 passes. This, as stated before, is arranged to enter the opening 20 in the tube 19. The lamp 30 may be raised or lowered by loosening the thimble 9 which, as shown in Fig. 1, is knurled to facilitate the turning of the thimble. The tube 7 may 85 now be adjusted with respect to the tube 4 and when in the desired position the thimble 9 may be tightened, thus causing the spring fingers 6^a to grip the tube 7 thereby holding it in position. The head 8^a is to prevent 90 the tube 7 from coming entirely out of the tube 4.

The thimble 12 when tightened will hold the laterally projecting arm 16 rigidly in position. Ordinarily, however, the thimble 100 12 would be loosened so as to permit the arm 16 to rotate. The loosening of the thimble 17 will permit the extension of the arm 16 so as to bring the lamp nearer to or farther away from the vertically extending 105 tube 7.

As will be seen from Fig. 1 the provision of the hinged joint 18 permits the swinging of the lamp from the full line position shown in Fig. 1 into other positions such as 110

those shown in dotted lines, where the lamp may be held by means of the set screw 18.

In Fig. 2 I have shown a modified form of the device in which a casing 24 is secured to the wall 25 and is provided with a rod or pipe 26 which is connected by an elbow 27 to the pipe 4. In this modification the conducting cord or cable 21 is designed to pass from the ceiling rosette (not shown) directly into the opening 20 shown in Fig. 1.

In Fig. 3 the casing 24* is secured to a table or other support 25* and the pipe or standard 28 is connected by an elbow 29 with the pipe 26 which in turn is connected by an elbow 27 to the pipe 4. In this modification, as in the one just described, the conducting cord is designed to extend from the ceiling rosette.

20 The pipes are designed to be of standard sizes and the material is preferably brass or bronze, but it will be understood that pipes of any suitable material and of any convenient size might be used without departing from the spirit and the scope of the invention.

I claim:

1. An electric light pendant comprising a pair of telescopic members, means for suspending one of said telescopic members, a sleeve mounted to turn on the lower end of the other of said telescopic members, the said sleeve projecting at its lower end below the end of said telescopic member, a laterally extending sleeve having a member secured in the projecting end of the first mentioned sleeve, and a slideable arm carried by said laterally extending sleeve for supporting a lamp.

40 2. An electric light pendant comprising a pair of telescopic members, means for suspending one of said telescopic members, a sleeve mounted to turn on the lower end of the other telescopic member, a laterally extending sleeve having a member secured to the lower end of said first mentioned sleeve, a slideable arm carried by said laterally extending sleeve for supporting a lamp, and means for retaining said telescopic members in their adjusted positions.

50 3. An electric light pendant comprising a pair of telescopic members, means for suspending one of said telescopic members, a sleeve mounted to turn on the lower end of the other telescopic member, a laterally extending sleeve having an upwardly extending member secured to the lower end of the first mentioned sleeve, a slideable arm carried by said laterally extending sleeve for supporting a lamp, means for retaining said telescopic members in their adjusted positions, and means for retaining said first mentioned sleeve in any of its adjusted positions on the said telescopic member.

60 4. An electric light pendant comprising a

pair of telescopic members, means for suspending one of said telescopic members, the other telescopic member having an annular flange at its lower end, a sleeve mounted to turn on the lower end of the last mentioned telescopic member and engaging said annular flange, the said sleeve having its lower end internally threaded and extending below the end of said telescopic member, a laterally extending sleeve having an upwardly extending threaded lug screwing in the end of the first mentioned sleeve, a slideable arm carried by said laterally extending sleeve for supporting a lamp, means for retaining said telescopic members in their adjusted positions, means for retaining said first mentioned sleeve in any of its adjusted positions, and means for clamping said slideable arm to said laterally extending sleeve.

5. An electric light pendant comprising a pair of telescopic members, means for suspending one of said telescopic members, a sleeve mounted to turn on the lower end of one of said telescopic members, a laterally extending sleeve having a lug secured in the end of the first mentioned sleeve, a slideable arm carried by said laterally extending sleeve for supporting a lamp, said slideable arm comprising two portions connected by a hinged joint, one of said portions bearing the lamp, and means for retaining the latter portion in any of its adjusted positions.

6. In an electric light pendant, a pair of telescopic supporting members, a sleeve carried by one of said members at the end thereof and arranged to receive the other member, a screw plug carried at the upper end of the last mentioned telescopic member and having a head fitting within the first member, said sleeve having a shoulder adapted to be engaged by said head, and spring fingers, and a thimble carried by said sleeve and arranged to engage said spring fingers for clamping the sleeve to said last mentioned telescopic member.

7. An electric light pendant, comprising a pair of telescopic members, means for suspending one of said members, a sleeve carried at the lower end of said member and through which the second telescopic member passes, a second sleeve mounted to turn on the lower end of said second telescopic member, means for clamping the sleeves to said second telescopic member, a laterally extending sleeve secured to the lower end of said second sleeve, a slideable arm carried by said laterally extending sleeve for supporting a lamp, and means for clamping said slideable arm to said laterally extending sleeve.

8. In an electric light pendant, a pair of telescopic supporting members, means for suspending one of said members, a sleeve mounted on the lower end of the other member and adjustable around the same, a later-

ally extending sleeve, means for securing the laterally extending sleeve to the lower end of the first mentioned sleeve, a slidable arm carried by the laterally extending sleeve for supporting a lamp, the said laterally extending sleeve having spring fingers at one end, and a thimble adjustable on the said end of

the sleeve for engaging the spring fingers to clamp the slidable arm in position.

WILLIAM OSCAR TEASDALE.
